(57) **CLAIM**

The ornamental design for a table base, as shown and described.

DESCRIPTION

FIG. 1 is a perspective view of a table base showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a perspective view to more fully illustrate the table base without a table top;

FIG. 8 is a perspective view of an alternate embodiment of a table base showing my new design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a perspective view to more fully illustrate the table base of FIG. 8 without a table top.

The phantom lines in FIGS. 1-6 and FIGS. 8-13 are for illustrative purposes only to show sample table tops and form no part of the claimed design. The bottom of each embodiment of the table base is not a part of the claimed design.
